N. MURPHY.
CURTAIN WINDOW LIGHT.
APPLICATION FILED JAN. 23, 1920.

1,424,511.

Patented Aug. 1, 1922.

Fig. 3.

UNITED STATES PATENT OFFICE.

NICHOLAS MURPHY, OF DETROIT, MICHIGAN.

CURTAIN-WINDOW LIGHT.

1,424,511.

Specification of Letters Patent. Patented Aug. 1, 1922.

Application filed January 23, 1920. Serial No. 353,499.

To all whom it may concern:

Be it known that I, NICHOLAS MURPHY, a citizen of the United States of America, residing at Detroit, in the county of Wayne and State of Michigan, have invented certain new and useful Improvements in Curtain-Window Lights, of which the following is a specification, reference being had therein to the accompanying drawings.

10 This invention relates to windows for vehicle curtains and its object is to provide a vehicle curtain window, the parts of which may be quickly assembled or disassembled and which avoids the use of rivets or similar fastening devices.

15 The invention consists in the various features of construction and arrangement of parts hereinafter fully described and illustrated in the accompanying drawings; wherein

20 Figure 1 is an interior view of the improved window applied to a curtain;

25 Figure 2 is a sectional view of the same taken on line 2—2 of Figure 1;

30 Figure 3 is a perspective view of the frame which holds the glass or other transparent member.

35 In these views the reference character A designates a vehicle curtain having the rectangular window opening A', and B is an open rectangular metal frame which is interiorly secured to the curtain bordering the opening A'. Said frame is flat on one side and on the other is provided at its outer edge with a marginal flange B', the flat side being adjacent the curtain. At the edges of the opening A' the curtain is formed with tongues or flaps C, which are passed through the central opening of the frame B and are

40 return-bent to overlap the inner face of said frame. Within the frame is mounted a plate D of glass or other transparent material which is retained in proper position with respect to the frame by the marginal flange B', said overlapping portions of the tongues C forming cushions between the glass and frame. Said tongues are provided with reduced end portions which project beyond the edges of the glass and are re-

45 turn-bent to overlap the inner face of the glass adjacent the margins of said face. To retain the glass in said frame and to clamp the tongues C between the glass and frame there are employed four channel

50 shaped resilient sheet metal members E, one of which engages each edge portion of the frame and the corresponding edge portion of the glass. The members E are so proportioned that they must be sprung slightly when being engaged with the frame and 55 glass so that they will securely embrace the engaged parts pressing the glass firmly into the frame and clamping the intermediate portions of the tongue C. The terminal portions of said tongues engaging between the 60 inner face of the glass and the members E form a cushion or packing protecting the glass from said clamping members.

65 From the foregoing description it is evident that the improved curtain window may be very quickly assembled or disassembled, the essential feature being the employment of resilient clamping members which retain the glass in the frame and at the same time firmly engage the tongues of the curtain between the glass and frame. By properly proportioning the channel-shaped clamps the same will very securely engage the frame and glass so as to avoid any possibility of 70 accidental displacement and yet may be removed when desired by merely exerting a 75 sharp pull upon the same.

80 What I claim as my invention is:

1. In a device of the character described, the combination with a curtain having a window opening, of a transparent member covering said opening, portions of the curtain engaging the edges and opposite sides of said member, and a plurality of quick detachable resilient clamping members of substantially U-shape in cross section frictionally securing said portions to said member.

2. In a device of the character described, the combination with a curtain having a window opening and formed with tongues at the edges of said opening, of an open frame bordering said opening, said tongues being passed through the opening and overlapped upon the frame, a transparent member mounted upon the frame and cushioned upon said overlapping tongues, and a plurality of resilient channel shaped members marginally engaging the glass and frame, retaining the same in engagement and clamping said tongues between the same.

3. In a device of the character described, the combination with a curtain having a

2
window opening, and formed with tongues at the edges of said opening, of an open frame bordering said opening formed with a marginal flange projecting from the curtain, 5 said tongues being passed through said frame and overlapped upon said frame, a transparent member mounted on said frame within said marginal flange and cushioned upon said overlapping tongues, and means 10 clamping the transparent member in the frame and clamping said tongues between the glass and frame.

4. In a device of the character described, the combination with a curtain having a 15 window opening and having tongues at the edges of said opening, of an open frame bordering said opening, the tongues being passed through said frame and bent to overlap the same, a transparent member mounted 20 upon said frame and cushioned on said overlapping tongues, the end portions of the tongues being return-bent to overlap the transparent member, and a plurality of channel shaped members marginally engaging 25 said frame and transparent member and retaining the same in engagement and clamping said tongues between the same, the end portions of the tongues forming cushions 30 between the transparent member and said clamping members.

5. In a device of the character described, the combination with a curtain having a window opening, of an open frame bordering said opening, a portion of said curtain marginal to said opening thereof being passed through and overlapped upon said frame, a transparent member mounted upon 35 said frame, and cushioned upon said overlapping portion of the curtain, and a channel shaped member embracing the glass and frame retaining the same in engagement, 40 clamping the curtain between the same.

6. In a device of the character described, the combination with a curtain having a 45 window opening of an open frame bordering said opening and formed with a marginal flange projecting from the curtain, a portion of the curtain marginal to the opening thereof being passed through said frame 50 and overlapped thereupon, a transparent member mounted in said frame within said marginal flange and cushioned upon said overlapping portion of the curtain, and quick detachable spring clamping means 55 curing said transparent member in the

frame, and clamping the curtain between said member and the frame.

7. In a device of the character described, the combination with a curtain having a window opening, of an open frame bordering said opening, a portion of the curtain marginal to the opening thereof being passed through said frame and overlapped thereupon, a transparent member mounted upon 60 said frame and cushioned on said overlapping portion of the curtain, said overlapping portion being return bent to overlap the transparent member, and a plurality of channel shaped members marginally engaging 65 said frame and transparent member and retaining the same, cushions being formed by said marginal portion of the curtain between the transparent member and said frame and clamping member respectively.

8. In a device of the character described, the combination with a curtain having a window opening, of a transparent member covering said opening, a portion of said curtain engaging the edges and opposite sides 70 of said transparent member, and a plurality of quickly detachable U-shaped clamping members frictionally embracing the edges 75 of said transparent member and retaining the portion of the curtain engaging said transparent member.

9. The combination with a window curtain having an opening therein, of a frame, a transparent member mounted in the frame, a plurality of removable channel shaped members clamping the frame and transparent member, and a plurality of tongues extending from said curtain at the edges of 80 said opening and passing between said transparent member and frame, and a portion 85 of said channel shaped member.

10. The combination with a window curtain having an opening formed therein, of a transparent member, a plurality of tongues extending from said curtain at the edges of said opening and engaging the edges and opposite sides of said transparent member, a frame of L-shape in cross section engaging the tongues at the edges and one side of said transparent member, and a plurality of resilient channel-shaped members engaging 100 the curtain and clamping the frame, transparent member and tongues.

In testimony whereof I affix my signature.

NICHOLAS MURPHY.
